United States Patent Office.

ROBERT BOYD AND JAMES C. HART, OF ROCHESTER, NEW YORK.

Design No. 4,504, dated December 13, 1870.

DESIGN FOR THE BASE OF A HOT-AIR FURNACE.

The Schedule referred to in these Letters Patent and making part of the same.

We, ROBERT BOYD and JAMES C. HART, of Rochester, in the county of Monroe and State of New York, have invented and produced a new and original Design for the Base of a Hot-Air Furnace, of which the following is a specification.

The nature of our design is fully represented in the accompanying drawing.

It consists of an octagonal base, B, for a hot-air furnace, A, two or more of the panels forming the faces of the base being ornamented with a tracery of straight diagonal bars, c c, formed thereon in bas-relief,

and arranged to intersect each other and form diamond-shaped recesses, x x, covering the entire panel, as clearly shown in the drawing.

We claim as our invention—

The design for the base of a heating-furnace, as herein described and illustrated.

ROBT. BOYD.
JAS. C. HART.
